(57) **CLAIM**

I claim an ornamental design for the measuring container, as shown and described.

DESCRIPTION

FIG. 1 is a perspective view of a measuring container showing my new design;

FIG. 2 is a front view of the measuring container, the back view being identical;

FIG. 3 is a top view of the measuring container;

FIG. 4 is a right side view of the measuring container, the left side view being identical; and,

FIG. 5 is a bottom view of the measuring container.

The broken lines represent a possible environment including a base element but form no part of the claimed design.
